CLAIM

The ornamental design for a ceiling fan, as shown and described.

DESCRIPTION

FIG. 1 is a perspective view of a ceiling fan according to a first configuration of my design;

FIG. 2 is a first side view of the ceiling fan of FIG. 1;

FIG. 3 is a bottom view of the ceiling fan of FIG. 1;

FIG. 4 is a top view of the ceiling fan of FIG. 1;

FIG. 5 is a second side view of the ceiling fan of FIG. 1;

FIG. 6 is a front view of the ceiling fan of FIG. 1;

FIG. 7 is a back view of the ceiling fan of FIG. 1;

FIG. 8 is a perspective view of the ceiling fan according to a second configuration of my design;

FIG. 9 is a first side view of the ceiling fan of FIG. 8;

FIG. 10 is a bottom view of the ceiling fan of FIG. 8;

FIG. 11 is a top view of the ceiling fan of FIG. 8;

FIG. 12 is a second side view of the ceiling fan of FIG. 8;

FIG. 13 is a front view of the ceiling fan of FIG. 8;

FIG. 14 is a back view of the ceiling fan of FIG. 8;

FIG. 15 is a perspective view of the ceiling fan according to a third configuration of my design;

FIG. 16 is a first side view of the ceiling fan of FIG. 15;

FIG. 17 is a bottom view of the ceiling fan of FIG. 15;

FIG. 18 is a top view of the ceiling fan of FIG. 15;

FIG. 19 is a second side view of the ceiling fan of FIG. 15;

FIG. 20 is a front view of the ceiling fan of FIG. 15;

FIG. 21 is a back view of the ceiling fan of FIG. 15;

FIG. 22 is a perspective view of the ceiling fan according to a fourth configuration of my design;

FIG. 23 is a first side view of the ceiling fan of FIG. 22;

FIG. 24 is a bottom view of the ceiling fan of FIG. 22;

FIG. 25 is a top view of the ceiling fan of FIG. 22;

FIG. 26 is a second side view of the ceiling fan of FIG. 22;

FIG. 27 is a front view of the ceiling fan of FIG. 22; and,

FIG. 28 is a back view of the ceiling fan of FIG. 22.

In the Figures, where shown, the broken lines shown are included for the purpose of illustrating portions of the article or its environment which form no part of the claimed design. The terms top, bottom, front and back are used for reference only and do not limit the claimed design.
